DESIGN FOR A METAL ORNAMENT FOR RINGS OR THE LIKE

Nathan Drilling, Brooklyn, N. Y.

Application March 23, 1937, Serial No. 68,360

Term of patent 7 years

To all whom it may concern:

Be it known that I, Nathan Drilling, a citizen of the United States, residing at No. 525 East 21st Street, in the Borough of Brooklyn, county of Kings, city of New York, and State of New York, have invented a new, original, and ornamental Design for a Metal Ornament for Rings or the like, of which the following is a specification, reference being had to the accompanying drawing, forming part thereof.

Fig. 1 is a front elevational view of a metal ornament for rings or the like showing my new design;

Fig. 2 is a side elevational view thereof.

I claim:

The ornamental design for a metal ornament for rings or the like as shown.

NATHAN DRILLING.
